METHOD OF DISPLAYING FIGURES AND
THE LIKE ON TRANSPARENT BODIESAnthony L. Normandi, San Francisco, and Gem-
ma Blanche Traversi, Petaluma, Calif.

Application November 1, 1937, Serial No. 172,244

1 Claim. (Cl. 41—22)

This invention relates to improvements in ornamentation and has particular reference to a novel method of decorating glassware and the like to produce thereon a figure or figures that have a 5 dual appearance, namely, a distinctive representation when viewed from the frontal view, and a distinctive novel representation when visualized from a rearward view.

The principal object of the invention is to provide 10 an entertaining, attractive, and amusing representation of a figure or figures, wherein the method employed is economical to manufacture, exceedingly durable, and highly effective.

Other objects and advantages will be apparent 15 during the course of the following description.

In the accompanying drawing forming a part 20 of this specification and in which like numerals are employed to designate like parts throughout the same;

Fig. 1 is a front elevation of a drinking glass, whereon there is shown in varied colors the front view of a female figure that has superimposed thereon wearing apparel; and

Fig. 2 is a similar view with the glass reversed, 25 showing the figure partly undraped to present an amusing and entertaining effect.

Our invention, in addition to its amusing and 30 entertaining aspect, comprises the novel steps resorted to in obtaining or realizing the composite figure illustrated in the drawing.

In the accompanying drawing wherein for the 35 purpose of illustration is shown a preferred embodiment of our invention, the numeral 3 designates a glass, which glass has retained therein water or other liquids. The figure is indicated by the reference character A and includes an upper torso 4, legs 5 and 6, arms 7 and 8, hair 9, a hat 10 and a dress 11.

In carrying out my process or method, a nude 40 or semi-nude figure is baked on a transparent background, such as glass; the hair is then painted thereon; the face is positioned over the hair; the coloring of the face is then added; and a costume, or wearing apparel or the like, is 45 painted over the figure. The trimmings on the dress are then ornamented, and thereafter, the

hands are painted. Thus, there is provided a nude or semi-nude figure that may be viewed from one side of the glass and a fully clothed figure to be viewed from the opposite side thereof.

Referring to the color design, the preferred 5 color effect is realized by painting the torso flesh color, the dress and trimmings blue, the hat, likewise, blue, and the ornaments of the hat white, while the color of yellow is given to the hair. These particular colors have been indicated by proper designations in the drawing; but it is to be understood that a variety of color effects may be employed, and, likewise, instead of figures, various fanciful displays may be illustrated, such as fences, or, in fact, any obstruction 10 that will interrupt the vision when viewed from the front of the glass, which obstruction will have a varied appearance from the frontal view.

It is to be pointed out that the figure, when 15 viewed from the rear, will be greatly enlarged as compared to the front view of said figure when water or other liquids are placed in the glass, thus the grotesqueness and amusing features of the ornamented glass are greatly enhanced.

In practice we also propose to resort to the use 20 of decalcomanias, which can be placed on the glass to realize the same effects as the preferred form of the invention.

It is to be understood that the method utilized, the figure shown, and the color effects employed 25 may be considerably varied without departing from the principle of the invention or the scope of the subjoined claim.

Having thus described our invention, we claim:

A method of decorating a transparent glass 30 tumbler or the like with a human figure to realize a dual appearance of said figure and consisting in first applying and then baking a nude figure on a surface of the glass and thereafter painting over the nude figure with suitable adornments of 35 various colors to simulate clothing, whereby the figure appears semi-nude when viewed from one side of the tumbler and fully clothed when viewed from the other side.
